UNITED STATES PATENT OFFICE.

PAUL MAUSER, OF OBERNDORF, GERMANY.

AUTOMATIC FIREARM.

1,130,312.

Specification of Letters Patent. Patented Mar. 2, 1915.

Application filed February 12, 1913. Serial No. 747,920.

To all whom it may concern:

Be it known that I, PAUL MAUSER, royal privy commercial councilor, a subject of the King of Wurttemberg, residing at Oberndorf-on-the-Neckar, in the Kingdom of Wurttemberg, Germany, have invented certain new and useful Improvements Relating to Automatic Firearms, of which the following is a full, clear, and exact description.

The invention relates to firearms with detachable magazine and means for locking the breech block in the open position after the last shot from the magazine is fired.

The invention has for its object to provide improved means for holding the breech block in the open position when the magazine is removed.

An embodiment of the invention is illustrated by way of example in the accompanying drawings, in which:—

Figure 1 shows the weapon partly in section and partly in elevation with magazine inserted. Fig. 2 shows the position of the parts with the magazine withdrawn. Figs. 3, 4 and 5 illustrate the bell crank lever which acts both as a locking member and an ejector in various elevations. Fig. 6 is a section like Fig. 1, but taken in a vertical plane behind that in Fig. 1. It shows the locking of the breech block by the cartridge follower. Fig. 7 is a section like Fig. 1, viewed from the other side, showing the coöperation of the rear wall w^1 of the magazine w with the projection k^3 of the lever k .

A member k , which acts both as locking member and ejector, presents the form of a bell crank or triangular lever and is pivotally mounted at g^1 in the frame g of the weapon. Its rear arm k^1 serves to lock the breech block when the magazine is withdrawn, while its front arm k^2 acts as an ejector when the magazine is inserted. The spring member k is acted upon by a spring f which is held in the frame by two clamps g^2 formed on the frame g and embrace the spring in the middle of its length on both sides (Fig. 1). This spring f serves also to hold the magazine w in the frame. For this purpose it is provided with a nose f^1 at its lower portion engaging a notch in the rear wall w^1 of the magazine (Fig. 1). When the magazine w is inserted, the lever k is held by the rear wall w^1 of the magazine acting on the projection k^3 of the lever k (Fig. 7) against the pressure of the spring f

in the position in which it acts (with its front arm k^2) as ejector (Fig. 1). When the last shot from the magazine is fired, the breech block v is locked after recoil in the rearward (open) position by the magazine follower w^2 (Fig. 6). Now the empty magazine is withdrawn to be replaced by a full one. Of course the magazine follower w^2 is also removed so that the breech block would be released and return into the forward (closed) position. But now the lever k which is no more locked by the magazine wall w^1 in the ejector position (Fig. 1) is rocked by the spring f acting on the stud k^4 so that the rear arm k^1 of the lever enters a recess v^1 in the breech block v thereby locking the same in the open position (Fig. 2). When the magazine is again inserted in the firearm its rear wall w^1 presses the projection k^3 of the lever k upward, so that the lever is again rocked in the ejector position (Fig. 1) against the action of the spring f . The breech block v is thereby released from engagement with the rear arm k^1 of the lever k so that it can freely move in the closed position. In this movement it pushes the first cartridge from the magazine into the barrel so that the arm is now again ready for firing.

What is claimed is:—

1. In a firearm, the combination of a breech block, a detachable magazine, a pivoted two-armed lever, one arm of said lever being adapted to act as an ejector when the magazine is in the frame, and the other arm being adapted to lock the breech block in the open position when the magazine is removed, and means for bringing said lever into locking engagement with said breech block, said means being adapted to be counteracted by said magazine to hold said lever out of locking engagement with said breech block.

2. In a firearm, the combination of a breech block, a detachable magazine, a pivoted two-armed lever, one arm of said lever being adapted to act as an ejector when the magazine is in the frame and the other arm being adapted to lock the breech block in the open position when the magazine is removed, and a spring for holding said magazine in the frame and adapted to press said lever into locking engagement with said breech block.

3. In a firearm, the combination of a breech block, a detachable magazine, means

connected with said magazine for locking said breech block in the open position after the last shot from the magazine is fired, and a pivoted two-armed lever, one arm of said lever being adapted to act as an ejector when the magazine is in the frame, and the other arm being adapted to hold the breech block in the open position when the magazine is removed, said magazine, when in position, holding said lever with its locking arm out of locking position.

4. In a firearm, the combination of a breech block, a detachable magazine, a cartridge follower adapted to lock said breech block in the open position after the last shot from the magazine is fired, and a piv-

oted two-armed lever, one arm of said lever being adapted to act as an ejector when the magazine is in the frame, and the other arm being adapted to hold the breech block in the open position when the magazine with the cartridge follower is removed, said magazine, when in position, holding said lever with its locking arm out of locking position.

In witness whereof, I have hereunto signed my name in the presence of two subscribing witnesses.

PAUL MAUSER.
